(57) **CLAIM**

The ornamental design for a portion of a display screen with icon, as shown and described.

DESCRIPTION

FIG. 1 is a front view of a portion of a display screen with icon according to a first embodiment of our design; and, FIG. 2 is a front view of a portion of a display screen with icon according to a second embodiment of our design.

The broken line showings of a portion of a display screen in the figures are environmental only and form no part of the claimed design.

Embodiments of the claimed designs of FIGS. 1 and 2 can be a portion of a display screen with icon in an autonomous vehicle.
